UNITED STATES PATENT OFFICE.

WILLIAM E. YOUNGER, OF SEATTLE, WASHINGTON.

ADVERTISING DEVICE.

1,038,057.

Specification of Letters Patent. Patented Sept. 10, 1912.

Application filed May 26, 1911. Serial No. 629,594.

To all whom it may concern:

Be it known that I, WILLIAM E. YOUNGER, a citizen of the United States, residing at Seattle, in the county of King and State of Washington, have invented new and useful Improvements in Advertising Devices, of which the following is a specification.

The invention relates to an advertising device, and more especially to the class of figure toys.

The primary object of the invention is the provision of a device of this character in which the body thereof is shaped and printed to represent an article of merchandise; for instance, the face of a soap cake, while the head is shaped similar to a boiler or wash tub, the same being printed to represent a face, and the arms and legs are jointed, whereby on operating the same, the figure will dance and pose in various attitudes, simulating life-like positions. Thus, in this manner, the figure will attract attention and give amusement, thereby serving as an advertising medium, it being understood of course that the advertising indicia of the body and head of the figure may be varied according to the wishes of the distributor of the figure.

Another object of the invention is the provision of a device of this character which represents an animated object, the same being provided with suitable configurations or indicia printed thereon, representing various mercantile commodities for displaying the same, and thereby serving as an advertising medium, the limbs of the figure being movable, so that the figure may be caused to assume various attitudes for attracting attention and giving amusement, when actuated by the possessor.

A further object of the invention is the provision of a device of this character which is simple in construction, and inexpensive in manufacture.

With these and other objects, in view, the invention consists in the construction, combination and arrangement of parts, as will be hereinafter more fully described, illustrated in the accompanying drawings, and pointed out in the claim hereunto appended.

In the drawings: Figure 1 is a front elevation of a figure toy constructed in accordance with the invention. Fig. 2 is a rear elevation thereof. Fig. 3 is a vertical longitudinal sectional view. Fig. 4 is a frag-

mentary rear elevation, the same being partly broken away.

Similar reference characters indicate corresponding parts throughout the several views of the drawings.

Referring to the drawings by numerals, the figure comprises a body 5, the latter being preferably constructed from card-board or other stiff material, and may be of any desirable shape, although in this instance, it is shown substantially rectangular, with rounded corners, the front face of the body 5 being provided with a border 6, representing one face of a cake of soap, and indicia 70 displaying the title or name of the soap as well as the maker thereof.

Formed at one end of the body 5 is a head 7 which may be of any desirable shape, and in this instance, is shown as the representation of a wash tub, the front face of the head 7 being provided with suitable configurations representing a human face or a character face.

Connected near the upper corners of the body 5 are swingingly mounted jointed arms, the forearms 9 being connected to the upper portions 10 of the arms by means of paper fasteners 11 forming pivots for the same, whereby the arms may be adjusted to assume different postures.

Connected near the lower corners of the body 5 are jointed legs, comprising outer and inner sections 12 and 13, respectively, the same being connected together by means of paper clips 14 forming pivots for the same, the arms and legs being connected to the body by means of similar paper clips 15 forming pivots for the said arms and legs, whereby they may move freely, so as to assume different postures.

Pasted or otherwise secured to the forearms, at the hand portions thereof, are rectangular-shaped pieces 16, on the front faces of which are printed representations of a soap cake and a box having suitable indicia thereon to indicate the nature of the soap cake and the contents of the box for advertising means.

Suitably secured to the rear face of the body 5 is a backing piece 17, the latter being provided with a guide way, in which is slidably fitted a push and pull strip 18, the same being also passed through a guide piece 19 mounted upon the back of the head 18 of the figure, the push and pull piece 18 being connected with a union cord 20 having

branches 21 connected in any suitable manner to the inner faces of the arms and legs, so that upon manipulation of the push and pull strip, the said arms and legs may be moved into different positions to suit the fancy of the possessor of the figure, for amusement purposes.

It is of course to be understood that the rear exposed surface of the body, head, legs and arms may be provided with suitable indicia designating similar representations to those on the front of the figure, if desired.

What is claimed is:

A device of the class described comprising

a body, jointed legs and arms pivotally connected adjacent the corners of said body, a head formed on said body, guide pieces, a push and pull strip slidably fitted in the openings in said guide pieces, and connections between the inner extremity of said strip and the arms and legs for moving the same.

In testimony whereof I affix my signature in presence of two witnesses.

WILLIAM E. YOUNGER.

Witnesses:
